Anthony Paul Limbach, Somerset, N.J., assignor to Mobil
Oil Corporation, a corporation of New York

Filed May 2, 1966, Ser. No. 2,095

Term of patent 14 years

(Cl. D9—225)

FIG. 1

FIG. 2

FIG. 3

FIG. 1 is a front perspective view of a merchandising container or the like showing my new design; and

FIG. 2 is a side perspective view thereof, said container being rotated 90°.

FIG. 3 is a cross-sectional view of the merchandising container or the like shown in FIG. 1 taken on line 3—3 thereof.

FIG. 4 is a cross-sectional view of the merchandising container or the like shown in FIG. 2 taken on line 4—4 thereof.

The dominant features of my design reside in the portion shown in full lines. The opposing sides of said container are identical.

I claim:

The ornamental design for a merchandising container or the like, substantially as shown and described.
